CLAIM

The ornamental design for a light for photography, as shown and described.

DESCRIPTION

FIG. 1 is a perspective view of a light for photography showing my new design;

FIG. 2 is another perspective view thereof;

FIG. 3 is a front elevation view thereof;

FIG. 4 is a rear elevation view thereof;

FIG. 5 is a left side elevation view thereof, the right side elevation view being a mirror image of FIG. 5;

FIG. 6 is a top plan view thereof;

FIG. 7 is a bottom plan view thereof;

FIG. 8 is a partial enlarged view of FIG. 1;

FIG. 9 is a partial enlarged view of FIG. 1;

FIG. 10 is a partial enlarged view of FIG. 1;

FIG. 11 is a partial enlarged view of FIG. 2;

FIG. 12 is a partial enlarged view of FIG. 2; and,

FIG. 13 is a partial enlarged view of FIG. 2.

The dash-dash broken lines in the figures are for the purposes of illustrating portions of the light for photography, which form no part of the claimed design. The dash-dash broken lines in the drawings depict boundaries of the enlarged portion and from no part of the claimed design.

1 Claim, 10 Drawing Sheets
